(57) **CLAIM**

The ornamental design for a "cradle for portable server monitor," as shown and described.

DESCRIPTION

FIG. 1 is a left, front perspective view of a first embodiment of a cradle for portable server monitor;

FIG. 2 is a front view thereof;

FIG. 3 is a top view thereof;

FIG. 4 is bottom view thereof;

FIG. 5 is a right side view thereof;

FIG. 6 is a left side view thereof;

FIG. 7 is a perspective view of a second embodiment identical to embodiment 1, but with the indicator lights lined for a different color;

FIG. 8 is a perspective view of a third embodiment identical to embodiment 1, but with the indicator lights lined for a different color;

FIG. 9 is a perspective view of a fourth embodiment identical to embodiment 1, but with the indicator lights lined for a different color;

FIG. 10 is a perspective view of embodiment 1, but showing a portable server monitor in broken lines; and,

FIG. 11 is a top view of embodiment 1, but showing a server rack in broken lines.

The features shown in broken lines are for illustrative purposes only and do not form part of the claimed design.
